UNITED STATES PATENT OFFICE.

JEREMIAH McGREVY, OF BROOKLYN, NEW YORK, ASSIGNOR TO SOLIDARITY WATCH CASE COMPANY, OF BROOKLYN, NEW YORK, A CORPORATION OF NEW YORK.

DESIGN FOR A RIBBON LOOP FOR WATCHCASES.

59,763.

Specification for Design.

Patented Nov. 22, 1921.

Application filed June 2, 1921. Serial No. 474,576. Term of patent 14 years.

To all whom it may concern:

Be it known that I, JEREMIAH McGREVY, a citizen of the United States, residing at Brooklyn, in the county of Kings and State of New York, have invented a new, original, and ornamental Design for a Ribbon Loop for Watchcases, of which the following is a specification, reference being had to the accompanying drawing, forming part hereof.

In the drawing,—

Figure 1 is a plan view of a ribbon loop for watch cases, showing my new design.

Fig. 2 is a similar view, the ribbon loop having been rotated slightly around its longitudinal axis.

Fig. 3 is a lateral view.

Fig. 4 is an end view.

I claim:—

The ornamental design for a ribbon loop for watchcases, as shown.

JEREMIAH McGREVY.
